TELEVISION REPRODUCER APPARATUS

Leonard Morris Myers, Middlesbrough, England,
assignor to Radio Corporation of America, a corporation of Delaware

Application April 13, 1938, Serial No. 201,700
In Great Britain March 8, 1938

6 Claims. (Cl. 250—150)

This invention relates to television reproducer apparatus and has for its object to provide improved television reproducer apparatus capable of producing powerful pictures suitable for projection. Great difficulties have been experienced hitherto in obtaining reproduction of television pictures of sufficient power for projection. The usual form of cathode ray tube in which the reproduced pictures are built up by scanning a 5 fluorescent screen has serious limitations as regards the light power which can be obtained from the fluorescent screen. The present invention seeks to avoid the limitations of the usual known form of cathode ray reproducer by providing an 10 improved form of reproducer of the kind wherein the reproduced pictures are obtained, not by fluorescent effect in a fluorescent screen, but by heating a picture reproducing electrode to incandescence and thus obtaining pictures by light 15 due to heat.

According to this invention a picture reproducing cathode ray tube having a screen which is to reproduce pictures by light due to heating is characterised in that the said heating is effected 20 at least in part by electron bombardment by a thermionic emitting electrode which is in turn heated to effect thermionic emission, said last mentioned heating being effected, at least in part, by an exploring cathode ray which bombards 25 and thus heats the said thermionic emitting electrode. Thus in carrying out the invention the thermionic emitting electrode, which will hereinafter be referred to as the "secondary cathode" is scanned by a picture signal modulated cathode 30 ray which accordingly causes localised heating (which is preferably additional to general pre-heating) and temperature increase in the secondary cathode and therefore produces from each individual point of its area, thermionic emission corresponding to the light or shade in 35 the corresponding point in the subject of transmission. The thermionic electrons thus emitted proceed to and are focussed upon the final picture reproducing screen (which may be termed an "incandescent anode") to heat it correspondingly and thus produce the final picture. The modulation of the cathode ray may be of any known type but intensity modulation is preferred.

The invention is illustrated in the accompanying drawing in which Fig. 1 shows a cathode ray tube, together with deflecting coil systems and optical system embodying my invention;

Fig. 2 shows in plane view the heating element of the thermionic emitting cathode embodied in 55 my invention; while

Fig. 3 shows in more detail in cross-section the structure of a thermionic emitting cathode in accordance with my invention.

Referring to Figure 1 which shows schematically one form of television reproducer cathode ray tube embodying the invention, the tube therein shown has an envelope with two neck portions 1, 2, and a central bulb portion 3 the diameter of which is at least four times that of the final anode or screen on which pictures are to be 10 reproduced, said bulb portion being made of the glass known under the registered trade-mark "Pyrex" or of some similar hard glass. In the neck portion 1 is an electron gun structure 4, of any form known per se, having associated therewith mutually perpendicular ray deflecting means constituted by mutually perpendicular deflecting coils. For simplicity in drawing these coils are represented merely by the rectangles 5 but it will be appreciated that there are two mutually perpendicular coils for line and framing deflection as in the well known way. The gun includes the usual control electrodes by which the intensity of the ray may be varied in accordance with picture signals and a short shielded coil 6 is provided for 15 magnetically focussing the ray. When the ray enters the bulb portion 3 its path is bent circularly (as indicated) by a magnetic field generated by a pair of coils (of which only one, 7, is shown) so that it enters the neck portion 2 and 20 scans a secondary cathode 8 capable of thermionic emission which is mounted in said neck portion 2. This cathode 8, whose preferred construction will be described later herein is subjected to 25 general heating from a source 9 and also to supplementary localised heating by the bombardment of the cathode ray and since the instantaneous value of the thermionic emission from any point in said cathode is dependent upon its instantaneous temperature there will be produced, 30 as it were, a "thermionic emission image" of the subject of transmission. Electrons thermionically emitted from the secondary cathode 8 are 35 drawn off by the action of a suitable positive electrode 10 forming part of an electron-optical system 10, 11, and entering the bulb portion follow 40 curved paths as indicated to fall upon the incandescent anode 12. A coil 13 is provided for 45 electron focussing purposes.

It will be seen that in the tube just generally 50 described the scanning cathode ray from the gun 4 forms what may be termed a "temperature image" on the secondary cathode 8 and this in turn produces a "thermionic emission image" from which the final light image on the incan- 55

descent anode 12 is obtained. 14 is a lens system for optical projection of the images formed on anode 12 on to a viewing screen (not shown).

To give a practical example—to which however the invention is not limited—the electron gun may be of the high beam current high potential type with the cathode at about -30,000 volts and the electrode nearest thereto (the Wehnelt cylinder) at about -20,000 volts relative to the potential of the secondary cathode 8. The rating may be about 40 to 60 watts. The intermediate cathode 8 is earthed. The final cathode or screen, which is preferably made as described later herein, may be maintained at about +5,000 volts relative to the secondary cathode 8. The electrode 11 is earthed and the electrode 10 may be maintained at about 2,000 volts positive in relation thereto.

There will now be described a preferred way of making the final anode or incandescent screen 12. As will be appreciated the requirement here to be satisfied for good definition is that the temperature rise shall be closely localised and there shall be a sufficiently steep temperature gradient to ensure that the heat spread (to incandescence) is not greater than about half the width of one scanning line. This requirement involves that the material which is to be heated to incandescence shall be slow to conduct heat away from a locally heated point and this in turn involves that the said material shall be very thin. Hitherto it has been found very difficult, if not impossible, to construct an incandescent type of screen sufficiently thin to satisfy these difficult requirements, and an important feature of the invention resides in solving this difficulty and thus obtaining improved results as regards fidelity and definition by providing the incandescent screen with a thin layer of lamp black under a protecting surface film of finely divided tungsten or other suitable material. In more detail, one way of making the screen 12 is as follows: A sheet of nickel or other convenient conductor is first coated with a thin deposition of lamp black in the form of a film about 0.004" thick. This coating may be conveniently effected by smoking the metal with a candle. Finely divided tungsten powder is then shaken through one or more thin meshes on to the surface of the lamp black film. If the mesh is fine enough the particles of tungsten appear to adhere to the surface of the lamp black so that even violent shaking will not disturb the surface film. The metal backing, with its lamp black layer and protecting surface film of finely divided tungsten, is then mounted in the tube envelope and is subjected to a de-gassing operation which is made as complete as possible. Owing to the low thermal conductivity of the lamp black screen such de-gassing cannot be satisfactorily accomplished as in the ordinary way with the aid of eddy current heating, and accordingly a filament for use in the de-gassing operation is introduced into the tube. This filament (not shown) which may consist of a suitable length of tungsten wire about 0.001" thick is supported about 1 cm. in front of the screen, and the said screen is de-gassed by using it as the anode of a diode whose cathode is constituted by the filament. The lamp black screen should receive about 100 watts per square centimetre in order to heat it up to and above the maximum working temperature to which it may be heated in subsequent use. When de-gassing is completed the filament can, if desired, be burnt out, but even if the filament is left in position it will not

seriously impair the picture since its width is substantially less than the normal width of a scanning line in picture reproduction.

The thermal conductivity of lamp black is very low as compared to that of tantalum, tungsten, or molybdenum—being less than one ten thousandth (it is of the order of 10^{-5} calories/cm. degree sec.)—and it has been found that if a thin film of lamp black of 0.004" in thickness or less is deposited on a metal plate (for example of nickel or tantalum) a temperature of over 2,000° C. on the plate is not appreciably conducted through the film. Furthermore, with a screen 12 made as just described, a picture scanning line of white hot intensity can be obtained on the surface with very little penetration of heat to the metal backing and very little heat "spread."

The protecting film of finely divided tungsten or other suitable metal is for the purpose of protecting the lamp black against evaporation in use for lamp black will evaporate in a high vacuum at temperatures higher than about 2,000° C.

As regards the secondary cathode 8 it will be appreciated that each point in the "temperature image" thereon will persist at an elevated though falling temperature for a substantial time (which must, of course, be less than the picture repetition period) after the scanning cathode ray which has caused its rise of temperature has passed on. Accordingly care must be taken to minimise spread of heat from point to point through the secondary cathode 8 so as to ensure that the heat spread will not be such as to spoil the detail.

A preferred form of secondary cathode 8 is made as follows: An independently heated nickel (or other suitable vacuum metal) film whose area is slightly greater than that of the "electron image" to be formed thereon is taken and is coated to a thickness of about 100 microns with a coating of barium and strontium carbonates on the side which is to be bombarded by the gun 4. The coating ensures that in actual operation the surface can be 100° C. (or thereabouts) hotter than the nickel carrier. The carbonates are then reduced to oxide by heating for a short time at about 950° C. in accordance with known technique. Then after activation of the cathode coating, the cathode is ready for use. In use the coating is heated by the independently heated nickel backing to about 800° C. and localised variations in temperature (to produce the "electron image") about this temperature are occasioned by the bombarding picture modulated cathode ray. The preferred construction of independently heated secondary cathode 8 consists of a tungsten wire heating grid clamped between two thin nickel plates and insulated therefrom by mica discs. Figure 2 shows the heating grid 8a and one of the mica discs 8b. Figure 3 represents in schematic section the cathode assembly 8a being the heater, 8b the mica discs, 8c the nickel plates (the clamps are not shown) and 8d the coating on one of these plates. One end of the heating grid 8a is connected to the coated nickel plate, i. e. the cathode proper. The whole assembly is mounted in an annular nickel or other suitable carrier mount (not shown). Preferably, before the coating 8d is deposited the cathode structure is fully outgassed by heating for a prolonged period in a separate bulb; it is then removed from this bulb, coated with the barium and strontium carbonate and sealed into the envelope in which it is to be employed, the coating

being then reduced to oxide and finally activated by operating with anode potential as known per se.

It is possible, though it is not preferred, to constitute the cathode 8 by a metal foil of a thickness of about 10^{-4} cms. the metal being of low specific heat and low density such as tungsten, nickel, molybdenum, tantalum or palladium. In order to secure the required thermionic emission from the metal foil it is coated on the face remote from the electron gun with a thermionically sensitive layer, for example a mono-molecular layer of caesium or barium. In the case of a tungsten foil secondary cathode, the foil should be first oxidised, for example by passing a discharge through oxygen at a pressure of about 2 mm. of mercury until the face of the foil acquires a suitable thickness of metal oxide as indicated by its observed colour. Then either barium or caesium is deposited on the film of oxidised metal by liberating the barium or caesium (as the case may be) from a suitable compound such as barium oxide or caesium chloride. A foil cathode so constructed can be subjected to direct general heating by a heating current passed through it to pre-heat it to about 800° C. Where a foil cathode is used the foil may be obtained by evaporating tantalum or other metal from a body of the metal which is positioned on a tungsten or similar electrically heated filament, the metal evaporated being evaporated upon a metal carrier so as to form a deposit thereon, the said metal carrier being afterwards removed to leave a foil. Examples of suitable carrier metals which may be used in manufacturing tantalum foils by this method are nickel, zinc and copper, nickel being preferred. One way of carrying out this method of obtaining the foil will now be described. There is employed a glass envelope with heavy current seals at each end and about 25 cms. in length. In this envelope is mounted a rectilinear tungsten filament to which electrical connection is made through the seals, the connection at least at one end being made through a zig-zag tungsten or other spring support so as to simplify glass blowing operations. The tungsten filament may be about 20 thousandths of an inch in diameter. A strip of tantalum, the metal from which the foil is to be formed, about 1 mm. in width and 2 thousandths of an inch in thickness is closely wrapped after the manner of a puttee about the tungsten. Co-axially surrounding the filament and suitably supported from the seals is a cylinder of nickel which constitutes the carrier metal upon which the tantalum is to be deposited. Assuming that a foil 10 cms. square is required, the diameter of the cylinder may be about 4 cms. The cylinder is so supported and insulated, e. g. by means of glass beads, as to prevent current being passed through it.

When the tungsten filament with its tantalum wrapping and the cylinder have been positioned in the envelope the said envelope is evacuated and current passed through the filament to give a temperature of about 2,000° C. This temperature is maintained for about half an hour in order to drive off occluded gases and during this operation the whole envelope may be baked in an oven at a temperature of about 400° C. When the degassing operation is completed the current through the filament is gradually increased until the tungsten is about to melt, that is to say, until it reaches a temperature of about 2,800° C. This temperature is, of course, below the melting point

of tungsten and slightly below that of tantalum. For the figures already given it will be found that a filament current of about 30 amps. and a power consumption of the order of 100 watts per inch length of filament will be required. The power radiated will be to a large extent absorbed by the surrounding nickel cylinder whose temperature will consequently rise until it glows a dull red. This nickel cylinder incidentally protects the glass walls of the envelope against collapse.

By occasionally switching off the filament current it is possible to observe the appearance of the inside of the nickel cylinder. When colour begins to appear on this inside surface the tantalum is starting to evaporate and at this stage the current through the filament should be controlled with caution. The amount of tantalum originally wrapped about the filament is chosen (by weight) to give the weight of foil finally required. Accordingly, the process above described is continued until all, or practically all, the tantalum is evaporated from the filament. If the filament current is carefully controlled, there is little fear of the tungsten evaporating. It has been found that a practical figure to adopt is 20.4 milligrams weight of tantalum per cm. of length of filament.

When the evaporation process has been completed the envelope is opened, and the nickel cylinder with the tantalum on the inside thereof is taken out, cut, and then rolled out flat into a sheet. The rolled out flat sheet is then immersed in water and sufficient nitric, sulphuric or other suitable acid added to start a reaction. The acid solution should be so weak that some time will be required to dissolve all the nickel and because of the length of time taken for this dissolving step in the process, it is advisable not to employ a nickel cylinder of too great thickness—a thickness of one half thousandth of an inch is sufficient. The acid solution employed should not be strong, for if it is too strong the tantalum foil may be ruptured due to too violent liberation of gas from the nickel.

Instead of removing the nickel by a chemical process as above described, the nickel cylinder with the tantalum deposit may be operated as an anode in another evacuated envelope having a filament which provides electronic emission. This filament is heated and electron discharge set up, the discharge device being so operated that the anode temperature becomes high enough to evaporate the nickel thus leaving behind the tantalum foil. Obviously in this method the anode (nickel-tantalum) should be so carried from its supports that when the nickel is evaporated, the remaining tantalum foil is still adequately supported. These supports may constitute the supports which will ultimately be required to carry the foil in the cathode ray tube for which it is intended.

It is advisable that supports be welded to the foil before the nickel is removed irrespective of the method adopted for removal. The supports should be of tantalum or molybdenum wire, preferably the former, and the weld between the supports and the foil should, of course, be made directly between the said foil and the said supports so that the removal or destruction of the nickel will not affect the said supports.

It is possible, but again it is not preferred, to constitute the final incandescent anode 12 by metal foil, for example, tungsten, tantalum or molybdenum, made as above described and about 10^{-4} cms. thick.

It will be appreciated that the total quantity

- of light given off from the incandescent anode 12 and therefore available for projection, is greatly increased by reason of the lag effect in the secondary cathode 8 from which the bombarding electrons are thermionically derived; that is to say, by reason of the fact that the temperature rise brought about at any picture element in the secondary cathode subsists for a substantial time after the causative scanning beam has passed.
- 10 If desired, the incandescent anode 12 may also be pre-heated either by passing a current therethrough or by arranging for there to be a constant component of electron bombardment from the secondary cathode.
- 15 Having now particularly described and ascertained the nature of my said invention and in what manner the same is to be performed, I declare that what I claim is:
1. A television picture reproducing cathode ray tube comprising an electron gun for projecting a beam of electrons, a planar thermionic electron emitting cathode positioned obliquely with respect to the electron gun and adapted to be bombarded by the projected beam of electrons, and a thermo-luminescent screen positioned obliquely with respect to said cathode and adapted to be bombarded by thermionic electrons released from said cathode by the impact of the electrons from the electron gun.
  2. A television picture reproducing cathode ray tube comprising an electron gun for projecting a beam of electrons, a planar thermionic electron emitting cathode positioned obliquely with respect to the electron gun and adapted to be bombarded by the projected beam of electrons, a thermo-luminescent screen positioned obliquely with respect to said cathode and adapted to be bombarded by thermionic electrons released from said cathode by the impact of the electrons from the electron gun, and cylindrical electrodes positioned intermediate said cathode and said screen for focusing thermionically emitted electrons upon said screen.
  3. A television picture reproducing cathode ray tube comprising an electron gun for projecting a beam of electrons, a planar thermionic electron emitting cathode positioned obliquely with respect to the electron gun and adapted to be bombarded

by the projected beam of electrons, means for heating the thermionic emitting cathode uniformly across the emitting surface thereof, and a thermo-luminescent screen positioned obliquely with respect to said cathode and adapted to be 5 bombarded by thermionic electrons released from said cathode by the impact of the electrons from the electron gun.

4. A television picture reproducing cathode ray tube comprising an axially aligned electron gun 10 for projecting a beam of electrons, a planar thermionic emitting cathode of extended area, said cathode being positioned at an acute angle with respect to the axis of the electron gun, a luminescent screen positioned at right angles with 15 respect to the axis of the electron gun and obliquely with respect to the thermionic electron emitting cathode, and electron focusing means positioned intermediate the cathode and the screen.

5. A television picture reproducing cathode ray tube comprising an axially aligned electron gun for projecting a beam of electrons, a planar thermionic emitting cathode of extended area, said cathode being positioned at an acute angle with 25 respect to the axis of the electron gun, a luminescent screen positioned at right angles with respect to the axis of the electron gun and obliquely with respect to the thermionic electron emitting cathode, electron focusing means positioned in 30 intermediate the cathode and the screen, and means for heating uniformly the thermionic emitting surface of the cathode.

6. A television picture reproducing cathode ray tube comprising an axially aligned electron gun 35 for projecting a beam of electrons, a thermionic emitting electrode positioned obliquely with respect to the axis of the electron gun and adapted to be scanned by the projected beam of electrons and to emit electrons from the same surface scanned by the beam of electrons, a thermo-luminescent screen adapted to be impacted by electrons released from said cathode by the impact 40 of the electrons from the electron gun, electron focusing means intermediate the cathode and the screen, and means for heating the emitting surface of the cathode uniformly.

LEONARD MORRIS MYERS.
